UNITED STATES PATENT OFFICE

2,684,883

COMBINATION COLLAPSIBLE TABLE AND
TRAY CONVERTIBLE WITHOUT RELEASE-
ING THE GRIP

Carl Wigell, Malmback, Sweden

Application November 14, 1951, Serial No. 256,214

4 Claims. (Cl. 311—85)

1

The present invention concerns an arrangement of a table with collapsible legs of the type where the table top is formed as a tray and the legs can be lowered and raised by means of actuating means located near the two carrying grips of the tray, and entirely separate from the carrying grips, without having the operation necessitate that the user release these carrying grips, so that the table can be used as a combination of serving tray and serving table. More specifically, the actuating means comprises at each end of the table a flat spring, a bracket with longitudinal slot and link arm, which guidably connects a pin fastened at the free end of the flat spring with a pin displaceably placed transversely in the slotted bracket.

The invention is characterized in that the lowering and raising are each brought about by a respective actuating handle, the handle being fastened on by members, for instance, in the form of circular discs which are in turn suitably mounted on a common axle between two ears projecting from the underside of the table top, which discs lie completely on the underside of the top and inside its edge, and in linked connection with the slotted link.

The invention is further characterized in that on the underside of the table top, directly above the discs, there is arranged a slit-shaped recess into which project the upper portions of the discs.

The invention is still further characterized in that that actuating handle which effects lowering of the legs is directly guidably connected by means of a link with the guide pin in the free end of the flat spring, while the other actuating handle, which effects the folding or raising of the leg, is guidably directed by means of a link with the center point on the link which connects the guide pin in the free end of the flat spring with the transversely placed pin that is 40

slidable in the slotted bracket.

It is further characterized in that the actuating handle which effects the lowering of the leg is so shaped, and the link which connects it with the guide pin in the free end of the spring, 45 is so long, that when the handle is pressed upward against the table board, it is able to lower the guide pin of the spring so far that the link which connects the guide pin of the spring with the slidable pin comes to be directed against the 50

section between the cross bar and the table top.

It is further characterized in that the actuating handle which effects lifting of the leg is so formed, and the link which guidably connects it with the center point on the link connecting 55

2

the guide pin in the spring end with the slidable pin, is so long that when the handle is pressed upwards against the table top, since the spring end is lifted, it is able to turn the cross bar and the leg well past the dead center point.

Additional characteristics are evident from the following detailed description.

The invention is illustrated in the accompanying drawings, in which:

10 Figure 1 shows a mode of execution of the arrangement partially in side section with the leg extended.

Figure 2 shows the same partially in side section with the leg folded.

Figure 3 shows the same seen from below, and Figure 4 is a fragmentary exploded perspective view, not to scale, showing the arrangement of the parts.

In the following, the mode of execution shown 20 is described in detail with reference to the drawings.

On the underside of the table top or tray 1 near each end and midway of the sides are attached two brackets with downwardly directed ears 6. In these ears is journaled a transverse axle 9, on which there are rotatably mounted between the ears two circular discs 7, 8, which extend partly into a recess 10 in the under surface of the table. These discs 7, 8 are each provided with an actuating handle 17, 18, respectively,

30 which extend in opposite directions laterally from the edge portions of the discs. One disc 7 is provided near its periphery at a distance of approximately 175° from its actuating handle 17 with a laterally projecting pin 19 about which is pivoted one end of a link 11 whose other end is pivoted about a pin 20 secured between the ends of a link 12. One end of the link 12 is pivoted by a pin 21 in the free end of a bracket 35 on the flat spring 13 while the other end of link 12 carries a pin 14, which is displaceable in the slot 16 of the bracket 15 on the cross bar 3 between the table legs 2. The second disc 8 is provided near its periphery at a distance of approximately 170° from its actuating handle 18 with a laterally projecting pin 25, to which is led a link 24, whose other end leads to the guide pin 21 in the free end of the bracket on the flat spring 13.

The discs 7, 8 are so dimensioned that a normal hand, which holds the table 1 with the thumb over the edge 5, where the actuating handles 17, 18 are located in their lowest position, is able to grasp the handle with the outermost sections of the other fingers.

The flat spring 13 is so shaped that when the leg 2 is lowered, as in Fig. 1, a peg 22 thereon engages in a hole 23 in the spring and locks the leg in the lowered or extended position, and so that the pin 21 thereby comes to lie directly outside the cross bar 3 and at an even level with its lower edge.

The link 12 is so long that in this position, the pin 14 lies against the outer end of the slot 16 in the bracket 15.

The link 11 is of such a length that when the leg assumes this lowered position, the pin 19 lies above and directly inside the inner edge of the ear 6 as seen from the table edge. The link 24 is of such length that when the leg 2 is folded up, as in Fig. 2, the pin 14 hits against the opposite (lower) side of the slot 16 and the upper side of the link 12 lies against the edge of the bracket 15 with the pin 21 higher than the pin 14, the pin 25 then lying above and directly inside the inner edge of the ear 6 as seen from the table edge.

Figure 4 of the drawings shows the relationships of the parts in diagrammatic form, the same being separated greatly for clarity, in the manner of an exploded perspective view. The proper scale of the parts, however, is better shown in Figs. 1 to 3, based upon an actual working embodiment.

The essential feature of the invention, and the one which makes the invention particularly desirable in connection with an article useful both as a tray and as a table or stand, is that the operating handles 17 and 18 are always pressed or squeezed upwardly, one in order to fold the legs up flat, the other to extend them into position to support the tray or top as a self-supporting table. It is not necessary for either handle to be manually moved downwardly or away from the tray, and thus operation to convert the device from one condition to the other can readily be carried out without the user having to relax his supporting grip upon the tray. Since a set of legs is provided at each opposite end of the tray (only one set being shown in the drawings), the user can convert the device from one use to the other merely by moving the ends of his fingers (of the hand at each end of the tray) from one operating handle to the other, these handles for each set of legs being placed close to one another to enable this to be done.

The principle of the invention can obviously be carried out with arrangements different from the details shown in the drawing; for example, the shapes of the operating handles, and so on, can be varied, so long as the essential relationship of the handles, discs (or their equivalents) and the like are maintained.

I claim:

1. A convertible table and tray device comprising a tray portion, leg assemblies at opposite ends thereof and hinged thereto for folding flat against the under side of the tray portion, a pair

of operating handles disposed beneath said tray portion and connected to each of said leg assemblies, and means connecting the operating handles of each pair to the corresponding leg assembly for operating the leg assembly selectively toward and away from its folded-up condition upon movement of a respective one of said operating handles in a direction toward the under side of said tray portion, said means comprising a first bracket secured to said leg assembly, a second bracket resiliently mounted for limited motion only with reference to said tray portion, a lever having a lost motion connection with said first bracket and pivoted in said second bracket, and a pair of links pivoted respectively to the center of said lever and to said second bracket, said operating handles being connected to said links respectively.

2. The invention in accordance with claim 1, in which said means comprises a first bracket secured to said leg assembly, a second bracket resiliently mounted for limited motion only with reference to said tray portion, a lever having a lost motion connection with said first bracket and pivoted in said second bracket, and a pair of links pivoted respectively to the center of said lever and to said second bracket, said operating handles being connected to said links respectively.

3. The invention in accordance with claim 1, including a pair of discs pivoted beneath said tray portion, one of said discs being pivotally connected to each of said links, and in which said operating handles are connected to said discs respectively.

4. Arrangement of table with collapsible legs of the type in which the table board is formed as a tray and the legs can be dropped down and lifted up by means of manipulating devices located near the two carrying grips of the tray, entirely separate from the carrying grip, without having the manipulation require the release of these carrying grips, so that the tray can be used as a combination of serving tray and serving table, and in which the manipulating device comprises at each table end a flat spring, a mounting bracket with a rectangular slot and a link which guidably connects a pin fastened in the free end of the flat spring with a transversely placed pin displaceable in the slot, characterized in that the dropping down and folding up of the legs is brought about each by its manipulating handle, which lies entirely on the underside of the tray and inside its edge.
